UNITED STATES PATENT OFFICE.

FREDRIK G. BORG, OF CHICAGO, ILLINOIS.

BRIDGE

No. 828,873.

Specification of Letters Patent.

Patented Aug. 21, 1906.

Application filed February 5, 1906. Serial No. 299,414.

To all whom it may concern:

Be it known that I, FREDRIK G. BORG, a citizen of the United States, and a resident of Chicago, in the county of Cook and State of Illinois, have invented certain new and useful Improvements in Bridges, of which the following is a specification.

This invention relates to bridges, and relates particularly to bascule-bridges.

Primary objects of the invention are to provide a counterweight applied to the bridge-span in such manner that it will exactly counterbalance said bridge-span in all positions; to provide a counterbalance in which the counterweight is applied to the bridge-span in such manner that said counterweight and its connections to said bridge-span will be above its point of application to said bridge-span in all positions, thereby rendering unnecessary a pit below said bridge to receive said counterweight and its connections, and to provide improved means for pivotally supporting said bridge-span whereby the supports for said bridge-span may be located entirely outside thereof, thus providing for bracing said bridge-span laterally throughout its length.

To effect these ends, my invention consists of the various features, combinations of features, and details of construction hereinafter described and claimed.

In the accompanying drawings, in which my invention is fully illustrated, Figures 1, 2, and 3 are side views of bascule-bridges, illustrating different ways of applying the counterweights thereto to effect the objects of my invention, said bridges being shown in open position in dotted lines, together with the counterweights and their connections to the bridge-spans in positions corresponding thereto; and Figs. 4 and 5 are partial sectional views on the line $x-x$ of Figs. 1, 2, and 3, showing different ways of pivoting the bridge-span.

Referring now to the drawings, A designates the spans of bascule-bridges, which as regards their usual features may be of any desired or approved construction.

The bridge-spans A are pivotally supported on suitable piers or columns B by means of trunnions C, and as regards my improved counterbalance the manner of pivotally supporting said bridge-spans is immaterial.

To effect the objects of my invention, as it relates to laterally bracing the bridge-spans throughout their entire lengths, the piers or

columns which support said bridge-spans are located entirely outside of said bridge-spans, thus providing unobstructed spaces between said piers or columns and providing for the use of spans braced laterally throughout their lengths in the desired manner. This object of my invention may be effected in two different ways, which I will now describe.

As shown in Fig. 4, trunnions C are revolvably mounted in a suitable bearing formed in the columns B and are secured against rotation in a suitable bearing on the bridge-span, requisite stiffness and rigidity being imparted to said trunnions by means of extensions c thereof, the remote ends of which are secured in a suitable bearing c', secured to the bridge-span at a distance from the main trunnion-bearings therein.

As shown in Fig. 5, the trunnions C are secured against rotation in suitable bearings in the columns B and in piers or columns B', located outside thereof, the inner ends of said trunnions C projecting inwardly and engaging suitable bearings on the bridge-span, so that said bridge-span will turn freely thereon.

As less strength is required in the trunnions C at points remote from the main bearings, the projecting ends c thereof may be tapered, as shown, for the purpose of saving stock.

I will now describe my invention as it relates to means for counterbalancing the same.

Broadly stated, my invention consists of a counterweight applied to the bridge-span through the medium of a compound lever comprising members pivotally connected, respectively, to a fixed support and to the shore end of the bridge-span at one end and to each other at their other ends, the relation being such that said lever members will be substantially parallel, respectively, to right lines, passing through the axis of the bridge-span trunnions and the points of pivotal attachment of the said lever members to said fixed support and bridge-span.

What I now consider the preferable embodiment of my invention is that shown in Fig. 1 of the drawings, referring to which D designates as a whole a compound lever comprising members 1 and 2. The member 1 is pivoted at a point 3 diagonally above the bridge-trunnion C to a suitable fixed support consisting, as shown, of an upward extension 4 of the bridge-span-supporting pier or column B. The lever member 2 is pivoted at

to the shore end of the bridge-span, preferably on a line passing through the axis of the trunnions and the center of gravity of the bridge-span. The opposite ends of the lever members 1 and 2 are pivotally connected to each other at 6, the relative lengths of said lever members being such that they will be substantially parallel the member 1 with a right line passing through the pivot-point 5 of the member 2 and the axis of the bridge-trunnions and the member 2 with a right line passing through the pivot-point 3 of the member 1 and the axis of said bridge-trunnions.

15 The counterweight 7 is pivotally connected at 8 to a carriage 9, which is movable along suitable guides formed on an upright support 10, and said counterweight is connected with the member 1 of the compound lever D by means of a strut 11, the lower end of which is pivotally connected to said lever member 1 at any desired point, as shown at a point outside of the point 6, at which the lever members 1 and 2 are pivoted to each other. My invention, however, contemplates pivoting said strut 11 to said lever member 1 either at or inside of the point 6, at which said lever members 1 and 2 are pivoted to each other.

20 The counterbalance shown in Fig. 2 comprises substantially the same elements as the counterbalance shown in Fig. 1—to wit, the bridge-span A, supported upon the piers or columns B by means of trunnions C, the compound lever D comprising the lever members 1' and 2', pivotally connected to each other at 6' at one end, and at their other ends, respectively, to the upward extension 4' of the supporting pier or column B and to the shore end of the bridge-span. As shown in Fig. 2, the counterweight 7' is secured directly to the outer end of the lever member 1, so that in operation it moves in the arc of a circle. Also owing to the different form of bridge-span A the upward extension 4' of the pier or column B extends rearwardly therefrom a greater distance than in Fig. 1 to provide sufficient room for the bridge-span A to open. As shown, also, the upper end of said extension 4' is supported by an additional column B², thus imparting requisite strength and stability to the structure.

25 The counterbalance shown in Fig. 3 likewise comprises substantially the same elements as are shown in Figs. 1 and 2—to wit, the bridge-span A, supported upon the piers or columns B by the trunnions C, the compound lever D, comprising the members 1² and 2², pivotally connected to each other at 6² at one end, and at their other ends, respectively, to the upward extension 4² of the piers or columns B and to the shore end of the bridge-span A, and the counterweight 7², applied to the lever member 1². As shown

in said Fig. 3, however, said counterweight is 65 movable on suitable guides formed on a standard or column 10² and is connected to the lever member 1² by means of a strut 11², pivotally connected to said counterweight at one end and to the lever member 1² at its opposite end. 70

75 My invention contemplates the use, either of separate counterweights 7 7' 7² applied to the bridge one at each side of the roadway by means of the described connections or a single counterweight which extends across and above the roadway and provided with the described connections to the bridge-span at both ends.

80 Any desired or approved means may be employed for opening and closing the bridge—as, for instance, a pinion 12, driven by means of suitable driving connection with any suitable motor and which engages a segmental gear 13 on the bridge-span in the usual manner, as indicated in Figs. 2 and 3, or, as indicated in Fig. 1, by means of a gear 14, revolvably mounted on the carriage 9, to which the counterweight 7 is connected, which engages a rack 15 on the standard 10 and to 85 which rotation is adapted to be imparted by means of driving connection with any suitable source of power. (Not shown.)

85 I have found that by applying the counterweight 7 7' 7² to the bridge-span by means of the compound lever D said counterweight acting through the lever member 2 2' 2² will create a component acting substantially at right angles to a right line connecting the point of pivotal connection of said lever member to the bridge-span with the axis of the trunnions C of said bridge-span, and thus tending to rotate the bridge, which will vary as the load opposed thereto varies as the bridge-span moves from closed to open position, or vice versa. It is thus obvious that by the use of a proper counterweight the bridge-span will be exactly counterbalanced in every position from its closed to its fully-opened position. 90

95 I claim—

1. In a bridge, the combination with a vertically-swinging bridge-span, of a counterbalance therefor, comprising a compound lever, comprising a member pivoted to a fixed support, a second member pivoted to said first member at one end and to the shore end of the bridge-span at its other end, the relation being such that said lever members will be substantially parallel, respectively, to right lines, one passing through the pivot of the bridge-span and the point of pivotal attachment of said second lever member to said bridge-span and the other through the pivot of said bridge-span and the point of pivotal attachment of said first lever member to its support, and a counterweight applied to said first lever member. 100

2. In a bridge, the combination with a vertically-swinging bridge, of a counterbalance therefor, comprising a compound lever comprising a member pivoted to a fixed support above the pivot of said bridge-span, a second member pivoted to said first member at one end and to the shore end of the bridge-span at its other end, the relation being such that said lever members will be substantially parallel, respectively, to right lines, one passing through the pivot of the bridge-span and the point of pivotal attachment of said second lever member to said bridge-span and the other through the pivot of said bridge-span and the point of pivotal attachment of said first lever member to its support, and a counterweight applied to said first lever member.
3. In a bridge, the combination with a vertically-swinging bridge-span, of a counterbalance therefor, comprising a compound lever comprising a member pivoted to a fixed support diagonally above the pivot of said bridge-span, a second member pivoted to said first member at one end and to the shore end of the bridge-span at its other end, the relation being such that said lever members will be substantially parallel, respectively, to right lines, one passing through the pivot of the bridge-span and the point of pivotal attachment of said second lever member to said bridge-span and the other through the pivot of said bridge-span and the point of pivotal attachment of said first lever member to its support, and a counterweight applied to said first lever member.
4. In a bridge, the combination with a vertically-swinging bridge-span, of a counterbalance therefor, comprising a compound lever, comprising a member pivoted to a fixed support, a second member pivoted to said first member at one end and to the shore end of the bridge-span at its other end, the relation being such that said lever members will be substantially parallel, respectively, to right lines, one passing through the pivot of the bridge-span and the point of pivotal attachment of said second lever member to said bridge-span and the other through the pivot of said bridge-span and the point of pivotal attachment of said first lever member to its support, and a counterweight applied to said first lever member.
5. In a bridge, the combination with a vertically-swinging bridge-span, of a counterbalance therefor, comprising a compound lever, comprising a member pivoted to a fixed support, a second member pivoted to said first member at one end and to the shore end of the bridge-span at its other end, the relation being such that said lever members will be substantially parallel, respectively, to right lines, one passing through the pivot of the bridge-span and the point of pivotal attachment of said second lever member to said bridge-span and the other through the pivot of said bridge-span and the point of pivotal attachment of said first lever member to its support, a counterweight, a support provided with guides, a head or carriage movably fitted to said guides, a strut pivotally connected to said head and to said first lever member and a counterweight carried on said strut.
6. The combination of a bridge-span comprising two trusses, supports therefor comprising only members located outside of the trusses of said bridge-span and means for pivoting said bridge-span to said supports comprising trunnions secured in one thereof which rotatably engage suitable bearings in the other, said bridge-span comprising a shore end which projects beyond the pivotal point thereof and is braced transversely below its pivotal point.
7. The combination of a bridge-span comprising two trusses, supports therefor comprising only members located outside of the trusses of said bridge-span and means for pivoting said bridge-span to said supports comprising trunnions secured against rotation in said supports and which engage suitable bearings on said bridge-span, said bridge-span comprising a shore end which projects beyond the pivotal point thereof and is braced transversely below its pivotal point.
- In testimony that I claim the foregoing as my invention I affix my signature, in presence of two subscribing witnesses, this 30th day of January, A. D. 1906.
